UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-CAN.

53,200.

Specification for Design.

Patented Apr. 15, 1919.

Application filed February 19, 1915. Serial No. 9,448. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Powder-Can, of which the following is a specification, reference being had to the accompanying drawing, forming a part thereof.

On the drawing:

The figure is a perspective view of the powder can embodying the said design.

The design is characterized by the combined configuration of the body, neck and cap; the body being cylindrical, and of a

height about equal to one-half of its diameter. The top of this body is flat except at its margin where it is formed with an upward swell or head; and a cylindrical neck rises from the center of said top and is surmounted by an overhanging perforated cap.

I claim:

The ornamental design for a powder can, as shown and described.

EDMUND HOFFMAN.
